TRAY FOR A WRAPPED TOMATO CONTAINER

Joseph E. Murphy, Hicksville, and Murray Schnall, Brooklyn, N. Y.

Application May 23, 1952, Serial No. 19,848

Term of patent 14 years

(Cl. D44—10)

To all whom it may concern:

Be it known that we, Joseph E. Murphy and Murray Schnall, both citizens of the United States, residents, respectively, of Hicksville, county of Nassau, Long Island, State of New York, and Brooklyn, county of Kings, city and State of New York, have invented a new, original, and ornamental Design for a Tray for a Wrapped Tomato Container, of which the following is a specification, reference being had to the accompanying drawing, forming part hereof.

In the drawing,

We claim:

The ornamental design for a tray for a wrapped tomato container, substantially as shown.

JOSEPH E. MURPHY.
MURRAY SCHNALL.
